FIXTURE FOR DISPLAYING MERCHANDISE

Anthony S. Miller, Jr., Vincentown, N.J., assignor to Col-O-Rac, Inc., Cherry Hill, N.J.

Original design application Oct. 16, 1970, Ser. No. 25,534, now Patent No. 225,703. Divided and this application
Mar. 3, 1972, Ser. No. 231,795

Term of patent 14 years

Int. Cl. D6—99

U.S. Cl. D6—28

FIG. 1

FIG. 5

FIG. 3

FIG. 4

FIG. 1 is a perspective view of a fixture for displaying merchandise showing my new design;

FIG. 2 is a top plan view thereof;

FIG. 3 is a side elevational view thereof;

FIG. 4 is a bottom plan view thereof; and

FIG. 5 is a perspective view of a modification of a fixture for displaying merchandise showing my new design, which modification differs from that of FIG. 1 by the replacement of the round base, column, table top and column top by a square base, column, table top and column top, respectively.

This application is a division of application Serial No. D-25,534, filed October 16, 1970, and entitled "Rack for Displaying Merchandise" and now U.S. Pat. No. D-225,703.

I claim:

The ornamental design for a fixture for displaying merchandise, substantially as shown and described.
